UNITED STATES PATENT OFFICE.

FRANK H. HANLEY, OF DETROIT, MICHIGAN.

ELECTRIC-IRON SWITCH.

Application filed February 9, 1923. Serial No. 617,916.

This invention relates to an electric iron switch, and has special reference to electric sad irons adapted to be placed in circuit with an ordinary electric light circuit, such irons including one or more resistance coils by which the ironing surface of the iron is heated for ironing purposes.

One of the objects of my invention is to furnish a switch attachment that may be easily and quickly installed on various types of irons now in use, without any material modification or change, and without interfering with the usual manipulation of the iron by the user.

Another object of this invention is to furnish the forward-end of an iron with a switch for controlling the current to the iron, the switch being constantly open and located contiguous to the iron handle so that the user of the iron may so retain a thumb or finger on the switch to hold it close during the use of the iron. With the switch otherwise open there is a saving in the expense of electric current, and the danger of fire and burning of goods is reduced to a minimum.

A further object of this invention is to furnish a constantly open electric iron switch with means for holding the switch closed so that the iron may be heated, preparatory to use, without the constant tension of the user. This same switch controlling means permits of the switch being locked in an open position so that it cannot be tampered with by those unfamiliar with the use of the switch.

A still further object of this invention is to provide a novel plug adapter or connector which will permit of the iron attachment being readily used in connection with an ordinary iron.

I attain the above and other objects by a simple, durable and inexpensive construction that will be hereinafter specifically described and then claimed, and reference will now be had to the drawings, wherein

Figure 1 is a side elevation of an iron provided with a switch, showing part of the switch removed;

Fig. 2 is a plan of the iron with the handle thereof in horizontal section and the plug removed;

Fig. 3 is an enlarged vertical sectional view of the electric iron, posts or jacks showing my adapter or connector;

Fig. 4 is a perspective view of an outer member of the connector;

Fig. 5 is a similar view of an intermediate part of the connector;

Fig. 6 is a perspective view of an inner member of the connector;

Fig. 7 is a cross sectional view of the iron handle showing a switch partly in section, and

Fig. 8 is a perspective view of a modified form of bracket.

In the drawings, the reference numeral 1 denotes a conventional form of electric iron having the rear end thereof provided with jacks or posts 2 and 3 which are ordinarily connected to the heating elements or units 70 within the iron. On top of the iron are bosses 4 provided with screw bolts 5 and 6 for holding the yoke 7 of the handle 8, said handle being attached to the yoke by screw bolts 9 and 10.

11 denotes a longitudinally disposed bracket arranged parallel to the yoke 7, at one side thereof, said bracket having a slotted side extension 12 extending under the head of the screw bolt 6 to be held thereby, as best shown in Fig. 2. At the forward end of the bracket 11 is an upstanding end portion 13 provided with a rearwardly extending angle lug 14 which protrudes into the forward end of the handle 8 and is sandwiched between said handle and the forward end of the yoke 7 to be held by the screw bolt 9. Since the screw bolts 6 and 9 form part of an ordinary iron the bracket 11 can be easily and quickly installed.

15 and 16 denote sections of a switch block preferably made of an insulation material, said sections being connected together by screws 17 and the switch block mounted on the forward end of the bracket 11, against the upstanding end 13 thereof, and connected to the angle lug 14 by a screw 18. The confronting faces of the block sections 15 and 16 have recesses 19 and 20. Slidable in the recesses 19 is a push button 21 having a plunger 22 provided with a collar 23 and a head 24, said collar and head being within the recesses 20. Encircling the plunger 22 in the recesses 19 is a coiled expansion spring 25 holding the push button 21 normally elevated with the collar 23 of the plunger limiting the upward movement of the push button, but not interfering with depression of the push button by a thumb or finger of the hand on the handle 8.

26 denotes binding posts in the recesses 20 and attached to one of the block sections,

said binding posts having opposed resilient contact members 27 adapted to be engaged by the head 24 of the plunger 22 when the push button 21 is depressed. The binding 5 posts 26 have leading out wires 28 extending through a conduit 29 suitably mounted on the bracket 11, said conduit having its forward end extending into the switch block.

10 30 denotes a double socket or plug detachably mounted on the posts 2 and 3 of the iron and said plug has the usual cable 31 for leading in wires or conductors adapted to conduct an electric current into the 15 iron. The plug also has sockets 32 and 33 with the latter slightly larger than the former in order that a connector can be interposed between the socket 33 and the post 3, said connector permitting of the 20 switch wires 28 being tapped in to one side of the electric circuit of the iron.

34 denotes an outer member; 35 an intermediate member, and 36 an inner member, said members being made of insulation 25 material and connected together by nut equipped screws 37 with some of said screws holding the connector on the rear downwardly inclined end 38 of the bracket 11. On one end of the member 34 is fixed a 30 thimble 39 of insulation material and fitted over this thimble is a metallic thimble 40 adapted to snugly fit in the socket 33. The thimbles 39 and 40 have flanged ends connected to the member 34 by rivets 41 and 35 one of said rivets is employed to hold a connecting strip 42 on the inner face of the member 34, said connecting strip being also held by a binding post 43 attached to the member 34 and to which binding post one 40 of the switch leading out wires 28 is connected.

44 denotes a plurality of yieldable fingers mounted on the member 36 and corresponding to an open thimble to receive the post 3. The fingers 44 are held in place by rivets 45 and one of said rivets assists in holding a connecting strip 46 on the member 36 so that a binding post 47 mounted in the members 34 and 35 may be electrically connected 50 with the fingers 44. The other switch leading out wire 28 is adapted to be connected to the binding post 47. The fingers 44 extend into the thimble 39 and through openings provided therefor in the members 34 and 35; the member 36 having an opening 48 which permits of the connector being placed down over the post 3, as shown in Fig. 3.

49 denotes a set screw carried by the 60 switch block section 16 and said set screw has its inner end provided with a pin 50 adapted to engage either under the push button 21 or in an annular groove 51 of the push button. When engaging under the

push button the switch is held in an open 65 position and the push button cannot be depressed. By depressing the push button 21 and screwing inwardly on the set screw 49 the pin 50 will engage in the groove 51 and hold the switch closed, thus completing a 70 circuit which causes the iron to be heated. The user can so set the switch providing the iron is on a suitable rest and after the iron has been heated the set screw 49 can be retracted to release the push button 21 and 75 permit the expansive force of the spring 25 to open the switch. The iron may then be placed in use and from time to time the switch closed by the thumb of the hand engaging the handle 8, and in this manner the 80 electric iron may be maintained at a desired temperature.

Since there may be various types of electric irons differing somewhat as to the location of the screw bolts 5 and 6, I may provide another form of bracket 52 and provide said bracket with an adjustable side extension 53 in lieu of the fixed side extension 12 of the bracket 11.

From the foregoing it will be noted that 90 the iron attachment includes the longitudinally disposed bracket with the switch at the forward end thereof and the connector at the rear end with the connector disposed so that it may be fitted down over one of the 95 usual posts of an electric iron, and when the attachment is properly installed the user of the iron can readily control the electric current by the switch at the forward end of the arm, without leaving the iron and operating any other switches.

While in the drawings there are illustrated the preferred embodiments of my invention, it is to be understood that the structural elements are susceptible to such changes in size, shape and manner of assembling, as fall within the scope of the appended claim.

What I claim is:—

A push button construction comprising 110 opposed block sections secured together and having the confronting faces of said sections cut away to provide outer and inner communicating recesses with the outer recess cylindrical to afford guide walls and the inner recess substantially rectangular, a spring distended circumferentially grooved plunger slideable in the outer cylindrical guide recess and extending into the inner 115 rectangular recess, contact members in the inner recess adapted to be engaged by said plunger, and a set screw in one of said block sections extending at a right angle to said plunger and adapted to secure said plunger in engagement with said contact 120 members.

In testimony whereof I affix my signature.
FRANK H. HANLEY.
